CLAIM

The ornamental design for a cap, as shown and described.

DESCRIPTION

FIG. 1 is a top perspective view of a cap showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top perspective view thereof, showing the cap in an environment in which it may be used.

The broken lines in FIG. 9 illustrating a bottle depict environment and form no part of the claimed design. All other broken lines depict portions of the cap that form no part of the claimed design.
